PROCESS FOR THE REMOVAL OF UNDESIRABLE SULPHUR COMPOUNDS FROM PETROLEUM OIL

Jackson R. Schonberg, Westfield, N. J., assignor to Standard Oil Development Company, a corporation of Delaware

Application October 5, 1940, Serial No. 359,840

1 Claim. (Cl. 196—31)

The present invention relates to a process for the treatment of mineral oils. The invention is more particularly concerned with an improvement in the treatment of petroleum oils for the removal of objectionable sulphur compounds therefrom with sulphuric or a similar acid under conditions in which unsaturated constituents are retained in the oil. In accordance with the present process, deleterious sulphur compounds are removed from petroleum oils boiling in the motor fuel boiling range by treating these oils with sulphuric or an equivalent acid and simultaneously agitating the mixture, controlling the temperature, and removing the heat of reaction by vaporization of a refrigerant throughout the mass of the oil.

It is well known in the art to treat mineral oils, particularly petroleum oils boiling in the motor fuel boiling range, with sulphuric or an equivalent acid in various refining and manufacturing operations. A conventional method for removing undesirable sulphur compounds from petroleum oil fractions is to treat the same with sulphuric acid. This method is not entirely satisfactory since the acid not only removes the undesirable sulphur compounds, but also tends to polymerize and remove valuable hydrocarbon constituents which materially improve the quality of the finished motor fuel. The loss of valuable constituents, due to the effect of sulphuric acid, varies widely, depending to a large extent upon the strength of the acid, the character of the stock being treated, and the temperature of treatment. However, when contacting the oil with acid at atmospheric temperatures under normal procedures, the loss when measured in terms of yields, lower clear octane numbers, and poorer susceptibilities of the finished stocks for knock suppressing agents is considerable in every instance. In order to overcome these disadvantages which are inherent in usual current processes utilizing sulphuric acid for the removal of objectionable sulphur compounds from petroleum oils, various modifications and different procedures have been suggested. For example, it has been proposed to employ relatively weak acids. These processes are not particularly desirable since it materially impairs the efficiency of the operation with respect to time required, daily capacity of the equipment, and the degree to which the objectionable sulphur compounds are removed. It has also been suggested that various diluents be utilized or that the treating operation be conducted at relatively low temper-

atures in the range from about 40° F. to 20° F. or below. At these temperatures the sulphuric acid apparently dissolves the undesirable sulphur compounds and will not dissolve or attack constituents which it is desired to retain in the finished motor fuel. These low temperature operations are not entirely satisfactory due to inherent difficulties and expenses involved in operating at temperatures appreciably below 70° F. to 80° F. Furthermore, at these low temperatures the activity of the acid in removing objectionable sulphur compounds, particularly when employing sulphuric acid, is considerably impaired, thus necessitating a material increase in the amount of acid required to secure a given sulphur reduction per given volume of oil being treated.

I have now discovered an improved process for removing objectionable sulphur compounds from petroleum oils containing the same. I have discovered that material benefits are secured with respect to sulphur removal and objectionable side reactions avoided, provided the heat of the reaction is immediately removed at the instant the acid reacts with the objectionable sulphur compounds which are being removed. In accordance with my invention a refrigerant is vaporized throughout the mass in order to remove the heat of reaction evolved and to maintain the temperature of the reaction somewhat below about 70° F. By operating in this manner, excellent mixing is secured and local overheating prevented. Furthermore, the body of the oil is maintained at substantially a constant temperature which permits treatment of the oil at higher temperatures where the activity of the acid in the removal of the objectionable sulphur compounds is not impaired and under conditions where deleterious polymerization of valuable oil constituents will not occur.

The process of my invention may be readily understood by reference to the attached drawings illustrating preferred modifications of the same. Figure 1 illustrates a process used in conjunction with an overall refining operation while Figure 2 illustrates a preferred type of acid contacting stage. Referring specifically to Figure 1, a feed oil, which for the purpose of illustration is assumed to be a petroleum crude oil, is introduced into distillation zone 1 by means of feed line 2. Distillation zone 1 may comprise any suitable number and arrangement of distillation units. Temperature and pressure conditions are adjusted to remove relatively high boiling con-

stituents by means of lines 3 and 4, and to remove overhead by means of line 5 hydrocarbon constituents boiling in the motor fuel boiling range. The overhead fraction is passed through condenser 6 and then introduced into separation zone 7 wherein uncondensed hydrocarbon constituents are separated from the condensate and removed overhead by means of line 8. The condensate is withdrawn from separation zone 7 by means of line 9 and introduced into stabilization zone 10, wherein temperature and pressure conditions are adjusted to completely free the hydrocarbon constituents boiling in the motor fuel boiling range of undesirable low boiling hydrocarbon constituents such as propane and the like which are removed overhead by means of line 11 and disposed of as desired. The stabilized product is withdrawn from stabilization zone 10 by means of line 12 and passed into acid treating zone 13. In this zone the oil, in accordance with the present invention, is intimately contacted with a mixture of acid and refrigerant which is introduced into acid treating zone 13 by means of lines 14 and 15. Acid treating zone 13 may comprise any number of stages or units arranged in any desirable manner. The acid sludge containing the objectionable sulphur compounds is withdrawn from acid treating zone 13 by means of line 16 and handled in any manner desirable. The acid oil, free of acid sludge, is withdrawn from acid treating zone 13 by means of line 17 and passed into neutralization zone 18 in which the oil is neutralized with a suitable alkali such as a caustic solution which is introduced by means of line 19 and withdrawn by means of line 20. The neutralized acid oil is then passed to redistillation unit 21 by means of line 22, in which temperature and pressure conditions are adjusted to remove overhead by means of line 23 a product having the desired end point. The overhead distillate is condensed in condenser 24 and passed to storage or otherwise handled by means of line 25. Unvaporized constituents are withdrawn from distillation zone 21 by means of line 26 and disposed of as desired.

A preferred modification of the present invention, particularly when employing a liquefied normally gaseous hydrocarbon as a refrigerant, is to segregate the refrigerant from the overhead vapors removed by means of line 11 in a separation zone 27. Conditions are adjusted to segregate a propane stream by means of line 28, and an ethane stream by means of line 29. The propane stream may be introduced into the acid by means of line 28 or withdrawn from the system by means of line 30. However, in general it is preferred to condense the ethane stream by condenser 31 or other suitable means and to pass the same to a separation zone 32 from which uncondensed constituents are withdrawn by means of line 33. This condensed ethane stream is then introduced into the acid by means of line 34.

Another preferred adaptation of the present invention, particularly when operating as described above, is to stabilize the oil during acid treating rather than prior to acid treating. If this preferred adaptation of the invention be utilized, the condensate withdrawn from the separation zone 7 by means of line 9 is passed directly into acid treating zone 13 by means of line 35, and the neutralized acid oil is passed through stabilization zone 36 by means of line 37 in which undesirable constituents are removed overhead by means of line 38 and the stabilized product removed by means of line 39.

Figure 2 illustrates a preferred modification

of the present invention and discloses in detail a method of contacting the feed oil with sulphuric acid and simultaneously agitating the mixture and removing the heat of reaction by vaporization of a refrigerant. Treating vessel 50 comprises treating stages M and N. Feed oil containing objectionable sulphur compounds is introduced into stage N by means of line 51. This oil upon entry into stage N simultaneously contacts acid withdrawn from stage M by means of line 52 and a refrigerant, which for the purposes of description is assumed to be propane, which is introduced by means of line 53. Pressure conditions are adjusted in stage N so that a sufficient quantity of propane is removed at a rate so as to remove the heat of reaction as it is evolved. The temperature of the oil introduced into stage N by means of line 51, therefore, remains substantially constant. The vaporized propane is withdrawn from stage N by means of line 54 and handled in any manner desirable, usually condensed and recycled to the system. The treated oil flows into the bottom of stage N in which the acid sludge separates and is withdrawn from stage N by means of line 55. The treated oil is withdrawn from stage N by means of pump 56 and line 57 and introduced into stage M. This oil simultaneously contacts fresh acid which is introduced into stage M by means of line 58 and additional propane which is introduced into stage M by means of line 59. Pressure conditions are adjusted in stage M to vaporize propane at a sufficient rate in order to remove the heat of reaction as it is evolved. The temperature of the oil in stage M thus does not substantially change. The vaporized propane is withdrawn from stage M by means of line 40 and handled in any manner desirable, usually by passing to compressor 41, condenser 42, and then recycling to the system. The treated mixture passes into the bottom of stage M, wherein an acid sludge layer and a treated oil layer separate. The acid sludge layer passes into stage N in the manner described and contacts fresh untreated oil. The treated oil is withdrawn from stage M by means of line 43 and handled in any manner desirable, usually soda washed, redistilled and then passed to motor fuel storage.

The process of the present invention may be widely varied. It may be applied in the treatment of any petroleum oil stock for the removal of objectionable sulphur compounds in which decomposition, polymerization, or side reactions occur when treating the same with sulphuric or an equivalent acid. The present invention is particularly applicable in the treatment of petroleum oil fractions boiling in the motor fuel boiling range for the removal of undesirable sulphur compounds and in which it is desired to have essentially substantially no reaction between the hydrocarbon constituents and the acid.

An essential feature of the invention is that the heat of reaction be removed immediately and that the temperature of the oil being treated be maintained in the range somewhat below about 70° F. In accordance with the present process, the acid and the oil are diluted by the evolved gas which removes the heat of reaction throughout the mass of liquid as it is formed. The evolution of propane throughout the mass, furthermore, materially increases the agitation of the mixture and thus prevents local overheating.

By operating in the manner described, the oil

may, if desired, be treated for the removal of objectionable sulphur compounds at substantially atmospheric temperatures in the range from 70° F. to 85° F. However the preferred operation is to cool the oil somewhat and to maintain the temperature of the cooled oil in this range without any substantial temperature change. By operating in accordance with the present process, very satisfactory results are secured by desulphurizing the oil at temperatures in the range from about 65° F. to 70° F., provided the temperature be maintained constant and that local overheating be eliminated by the vaporization of the refrigerant throughout the mass at the instant the acid contacts the oil. When operating in this manner the oil is cooled prior to contacting the same with acid so that it is not necessary to chill the oil in contact with the acid and so that a substantial constant temperature is maintained. It is essential for the present process that the temperature of the oil being treated upon contact with the acid does not substantially vary. In accordance with the desired modification, the temperature of the feed oil being treated upon contact with the acid should not vary over a temperature range over about 5° F., preferably not over 2° F.

Although any suitable refrigerant may be employed, as for example, sulphur dioxide, and the like, I have found that particularly desirable results are secured, provided the refrigerant be a liquefied normally gaseous hydrocarbon. In general, it is preferred that the refrigerant should be a saturated hydrocarbon, such as propane. Under certain conditions it may be desirable to employ a refrigerant comprising a mixture of propane and butane. However, a particularly desirable solvent comprises ethane free of higher boiling hydrocarbons. It is especially preferred that the refrigerant be mixed with the acid before the acid contacts the oil and that the pres-

sure be reduced when contact is secured, thus immediately removing the heat of the reaction. The amount of refrigerant added to the fresh acid is sufficient to fully remove the entire heat of reaction in the respective stages and to maintain the temperature at the desired level. If this procedure be carried out, conditions are adjusted so that the correct amount of refrigerant is vaporized in the individual stage at the 5 desired rate to remove the heat of reaction from the respective stage and to maintain the oil at substantially a constant temperature. However, in general, it is preferred to employ an 10 operation in which the correct amount of refrigerant is added in each individual stage in 15 order to remove the heat of reaction from that stage at the desired rate. Another preferred modification, particularly when employing light petroleum hydrocarbons as the refrigerant, is to acid treat the oil prior to stabilizing the 20 same.

The process of the present invention is not 25 to be limited by any theory or mode of operation, but only in and by the following claim in which it is desired to claim all novelty in so far as the prior art permits.

I claim:

Process for the removal of undesirable sulphur compounds from petroleum oils boiling in the 30 motor fuel boiling range under conditions to retain the major part of the unsaturated constituents in the treated oil, comprising treating said petroleum oil at a temperature in excess of about 65° F. with a mixture comprising sulphuric acid and a liquefied saturated normally gaseous hydrocarbon under conditions to vaporize said liquefied hydrocarbon throughout the mass and to remove the heat of reaction as it is formed so 35 that temperatures above 70° F. are avoided, whereby excessive polymerization and side reactions are prevented.

JACKSON R. SCHONBERG.
